UNITED STATES PATENT OFFICE

JAMES W. ESTES, OF BIRMINGHAM, ALABAMA

AMUSEMENT APPARATUS

Application filed October 9, 1929. Serial No. 398,413.

The present invention appertains to improvements in amusement apparatus and more particularly to a novel roundabout.

The principal object of the invention is to provide a novel roundabout form of amusement apparatus embodying in operation a new and highly amusing series of tortuous movements.

Another important object of the invention is to provide a roundabout constructed to accommodate a number of people and which in operation will be safe and not liable to the development of defects which now occur in this character of amusement.

These and other important objects of the invention will become more apparent to the reader after considering the invention as described and claimed hereinafter.

In the drawings:—

Figure 1 represents a fragmentary top plan view, showing substantially one-half of the improved apparatus.

Fig. 2 represents a fragmentary top plan view of substantially half of the apparatus, and showing the panels and cars removed therefrom.

Fig. 3 represents a top plan view of the stationary platform and its sectional racks.

Fig. 4 represents a fragmentary vertical sectional view.

Fig. 5 represents a bottom plan view of one of the radial frames in which the means for moving a car is located.

Fig. 6 represents a fragmentary vertical sectional view through one of the frames and the car movable thereon.

Fig. 7 represents a vertical sectional view through the mobile platform and transversely through one of the frames and showing a car in end elevation thereof.

Fig. 8 represents a fragmentary vertical sectional view through the inner end portion of one of the frames and the adjacent edge portion of the stationary platform.

Fig. 9 represents a fragmentary vertical sectional view transversely through one of the frames, at the inner end portion thereof.

Fig. 10 represents a vertical transverse sectional view through the lower end portion of one of the frames.

Fig. 11 represents a fragmentary longitudinal vertical sectional view through the lower end portion of one of the frames.

Fig. 12 represents a fragmentary vertical sectional view through the edge portion of 55 the stationary platform.

Fig. 13 represents a perspective view of a guide member employed in the invention.

Fig. 14 represents a perspective view of the U-shaped member employed for supporting one of the pulleys on the frame shown in Fig. 5.

Fig. 15 is a perspective view of a cap member employed in the frame construction.

Referring to the drawings wherein like numerals designate like parts, it will be seen that the present invention embodies a stationary platform generally referred to by the numeral 5 and a movable platform generally referred to by numeral 6. The stationary platform consists in the construction of a circular support 7 elevated above the ground by suitable legs 8 and being provided with an upstanding shaft 9.

The shaft 9 is stationary and is secured to the support 7 by the base plate 10. The shaft 9 has a hub 11 rotatably mounted thereon, and supported upon the base 10 and a circumferentially extending flange 12, projects from this hub.

An annular angle bar 13 is secured upon the support 7 and has its inner side provided with groups of rack teeth 14 at equal spaced intervals. Secured to the support 7 and in parallel relation to those portions of the annular angle bar 13, not provided with rack teeth are the arcuate shaped angle bars 15 provided with rack teeth 16 at their sides opposing the annulus 13. At the end of each arcuate bar 15, a plate 17 is secured to the support 7, and this plate has a longitudinally curved flange 18 upstanding thereon, and a relatively short plate 19 rising therefrom in parallel relation to the flange 18.

The end portions 20 of the plate 19 are 95 obliquely disposed away from the flange 18 in the manner clearly shown in Fig. 13. The annular mobile platform 6 is built up of a plurality of frames generally referred to by the numeral 21 in Fig. 5. Each frame con-

sists of a pair of elongated angle bars 22—22 arranged in parallel spaced relation and connected together at one end by the cap member 23, shown perspectively in Fig. 15. The cap member 23 is provided with an opening 24, through which a set screw 25 is slidably disposed and threadedly engaged through the bight portion 26 of the U-shaped member 27.

10 The U-shaped member has the ends of its legs provided with openings 28 for receiving a pin on which a pulley 29 is mounted. A slide plate 30 is slidably mounted within the frame, and carries a pair of rollers 31—31 for engaging one flange of the frame.

15 A hollow shaft 32 has its threaded solid end portion 33 disposed between the spaced angle bars 22—22 and limited in its downward movement by a circumferential flange 34. The plate 30 has a sleeve 35 depending therefrom and the threaded solid end of the shaft 32 is disposed therethrough, and adapted for receiving a nut 36 and a washer 37 for maintaining the spool 38 against the 20 slide plate 30 in the manner shown in Fig. 5. A pulley 39 is carried on the spool 38 and is of slightly less diameter than the spool 38, so that the spool will ride against the depending flanges of the bars 22—22.

25 30 As is clearly shown in Fig. 6, a car generally referred to by the numeral 40 includes the seat 41 having the back 42 and side walls 43. A floor 44 is also provided with a toe board 45. The toe board 45 has an inwardly disposed bracket 46 at its upper end for rotatably receiving the upper end of a shaft 47. The shaft 47 extends through a bushing 48 in the floor 44 and a yoke 49 at the lower end of the shaft rotatably carries a wheel 50.

35 40 A shaft 51 depends from the seat 41 and also has a yoke 52 for rotatably receiving a wheel 53. The seat 41 also has a rack 54 which depends therefrom and into the hollow shaft 32 in the manner clearly shown. 45 As is clearly shown in Fig. 7 there are a pair of the shafts 51 and the wheels 53 and these are adapted to ride on elongated wear plates 55—55 on the edge portions of panels 56 connecting the radially disposed frames shown 50 in Fig. 2.

These frames radiate from the stationary platform and the panels aforementioned connect the frames to form an annular mobile platform. Each frame has a cross-piece 57 at its intermediacy and to the ends of these cross pieces are connecting members 58 for bracing and retaining the frames in the radial disposition.

60 65 The mobile platform is transversely inclined outwardly and at the lower end of each frame is a U-shaped wheel mount 59 having its upper end bent outwardly and secured to the frame as at 60. The lower bight portion of the mount is secured to an angle

member 61 to which a wheel 62 is rotatably connected.

The upper end of each frame has a drum 63 rotatably mounted therein by a pin 64. The pin 64 has a head 65 thereon for supporting the drum within the frame, while the drum is provided with a pair of centrally located lugs 66—66 for universally receiving the upper end of the shaft 67. The shaft 67 depends downwardly and has a pinion 68 secured to its lower end and a pintle 69 extending below the pinion, and being engageable at times between the flange 18 and the plate 19 on the plate 17, at the ends of the arcuate angle bars 15.

70 75 The inner ends of the frames are connected by angle bars 70 and members 71 depend from the angle bar sections 70 and connect to an annulus 72. A pin 73 is secured to the annulus 72 and projects through the hub 74 of a wheel 75, adapted to ride upon the outwardly disposed flange of the annular angle bar 13 shown in Fig. 3. A spacer 76 is interposed between the hub 74 and the depending member 71. Brace bars 77 and 78 extend from the angle bar sections 70 and annulus 72 respectively for connection to the flange 12 on the hub 11.

80 85 As is clearly shown in Figs. 5 and 9 a flexible strand 79 is convoluted about the drum 63 with one end secured to one end of the slide plate 30 and the opposite end portion disposed past the pulley 39 and around the pulley 29 for connection to the opposite end of the plate 30.

90 95 It will thus be seen that when the hub 11 is rotatable by any suitable means, the aforementioned connections between the same and the annular mobile platform will result in the rotation of the same. The rotation of the mobile platform, will result in the reciprocation of the cars 40 on the wear plates 55—55, due to the particular gear and strand connection between the stationary platform and the said cars. Thus an irregular movement of the cars in reciprocatory movement back and forth across the mobile platform, will occur during the rotation of the annular platform, so that considerable amusement will be afforded by patrons riding on the cars. 100 105 110 115

Furthermore, while the foregoing description has been in somewhat specific terms, it is to be understood that various changes in the specific shape, size, and materials may be resorted to without departing from the spirit and scope of the invention as described hereinafter.

Having thus described my invention, what I claim as new is:—

125 1. A roundabout amusement device comprising a stationary platform, an annular mobile platform encircling said stationary platform, said mobile platform consisting of a plurality of rectangular frames extending radially from said stationary platform in 130

- a position declining therefrom, seats slidable on said frames, each of said seats being provided with a depending member, a pulley wheel rotatably mounted on the lower end 5 of the member, a rotary element at each end of each frame, a plate carried by the depending member of the corresponding seat, a flexible element trained about the rotary elements at the ends of the frames and secured at its 10 ends to the said plate, the said flexible element being engaged with the pulley wheel on the depending member of the corresponding seat, and means for rotating one of the said rotary elements at the ends of the frame.
- 15 2. In a structure of the class described, a stationary platform, an annular movable platform encircling said stationary platform and embodying a plurality of radial frames, seats movable on said annular platform and 20 having shafts extending through said frames and having plates underlying the frames, pulleys adjacent the inner and outer ends of said frames, flexible elements chained about said pulleys and connected at the ends thereof 25 with said plates, and driving means engaged with one of said pulleys to turn the same alternately in opposite directions and thereby bring about inward and outward movement of said seats.
- 30 3. In a roundabout amusement device, a central stationary platform, a plurality of arcuate rack bars on said platform, vertical shafts having gears for engagement with said rack bars, said shafts being provided 35 with pilot portions below said gears, guiding devices at the end portions of said bars and consisting of inner and outer upstanding flanges, the outer flanges having the end portions thereof directed outwardly, an annular 40 platform movable about said first named platform and having radially movable seats, and a connection between said radially movable seats and said shafts to transmit the movement of said shaft to said seats.
- 45 4. In a roundabout amusement device, a central stationary platform, a plurality of arcuate rack bars on said platform, vertical shafts having gears for engagement with said rack bars, said shafts being provided 50 with pilot portions below said gears, guiding devices at the end portions of said bars and consisting of inner and outer upstanding flanges, the outer flanges having the end portions thereof directed outwardly, an annular 55 platform movable about said first named platform and having radially movable seats, and a connection between said radially movable seats, and said shafts to transmit the movement of said shaft to said seats, said connection between said shafts and said seats being universal.
- 60 In testimony whereof I affix my signature.
JAMES W. ESTES.
